COIN-CONTROLLED SELECTOR CIRCUIT
FOR PHONOGRAFSAlfred E. Reiman, Chicago, Ill., assignor to
Rock-Ola Manufacturing Corporation, Chicago,
Ill., a corporation of Illinois

Application October 27, 1947, Serial No. 782,389

4 Claims. (Cl. 194—15)

1

This invention relates in general to selectively operable coin-controlled machines, and more particularly to automatic, multi-record, coin-controlled phonographs.

In some prior art devices of this type in which a plurality of selector control members are selectively operable to determine the playing of different records, or to control successive cycles of operation, and the number or value of coins deposited determines the number of cyclic operations or playing cycles, after a coin or coins have been deposited to render the mechanism operable for a plurality of cycles and a corresponding number of selector control members have been operated, there is nothing in the machine to prevent someone else, at any time between the starting of the first and of the last cycle selected, from appropriating the remaining playing cycles merely by actuating certain others of the selector control members.

A principal object of this invention is the provision of novel control mechanism for such phonographs, or other similar coin-controlled and cyclically operable devices, which prevents loss of the selections made by the person who has deposited the coins, by rendering ineffective any actuation of the selector control members after the deposit of a coin or coins and the making of a corresponding number of selections by operation of such selector control members.

Another object of the invention is to provide in such devices novel operation control mechanism which includes normally inoperative selector control members rendered operative by the deposit of a genuine coin or coins of the proper value, and thereafter selectively operable to predetermine the records to be played, but only for the number of cycles of the machine corresponding to the value of the coin or coins deposited, the deposit of each predetermined incremental coin value, such as five cents, rendering the selector control members operative to effect one cycle of operation of the machine.

A further object of the invention is the provision of such operation control mechanism comprising normally inoperative selector control members, accumulator mechanism automatically operable positively, in response to the deposit of proper coins, to accumulate the total of the predetermined incremental values represented by the coin or coins deposited and to render the selector control members operative each to select a record for playing, and mechanism operable immediately in response to subsequent operation of any selector control member to actuate the accumulator mechanism negatively to subtract the pre-

2

determined incremental value from the total therein accumulated, the accumulator mechanism being operable upon its return to normal condition or zero position, by successive negative incremental operations equal to the previously effected total positive coin-responsive actuation thereof, to render all of the selector control members inoperative.

Since the instant control mechanism includes 10 means for effecting a debiting or negative actuation of the accumulator as each selection is made by operation of a selector control member, and means for effecting a positive actuation of the accumulator in response to the deposit of any 15 acceptable coin or coins, another object of this invention is to prevent simultaneous operation of these two means for effecting opposite actuations of the accumulator to avoid jamming or breakage of the parts thereof.

20 More specifically, such prevention of simultaneous actuations of the accumulator in opposite directions is accomplished by a normally closed lock-out switch interposed in the accumulator debiting mechanism control circuit, which is 25 automatically opened to break such circuit during positive actuation of the accumulator in response to the deposit of an acceptable coin.

A further object of the invention is the provision in such an operation control mechanism of an interlocking switch arrangement or assembly 30 normally operable to maintain the control circuit of the accumulator debiting mechanism open to prevent actuation of any selector control member from being effective, automatically operable upon deposit of any proper coin or coins 35 to condition such circuit for closing by subsequent actuation of any selector control member, and automatically operable back to normal condition in response to operation of a selector control member. If more than one increment or unit of 40 value has been entered positively in the accumulator mechanism by the deposit of more than one coin or of a proper coin having a multiple unit value, this interlocking switch arrangement will 45 continue to be operated automatically after each actuation of a selector control member to again condition the circuit for closing by subsequent actuation of any selector control member, until the accumulator mechanism has been returned 50 to zero by repeated operations of the debiting mechanism in response to a number of actuations of selector control members equal to the total number of units or incremental values positively accumulated responsive to coin deposits, when the 55 interlocking switch arrangement will be main-

tained in normal condition to render ineffective all selector control members.

Thus another object of the invention is to maintain the selector mechanism inoperative in an automatic phonograph until a proper coin has been deposited, and then automatically to render the selector mechanism effective only in response to the first selections made, one at a time or serially, in number equal to the total units of value of the coin or coins deposited.

A further important object of the invention is the provision in such an automatic phonograph having a plurality of manually operable selector members, which are numbered serially in accordance with the number of records contained in the phonograph, of interlocking mechanism associated with such selector members and automatically operable in response to and during actuation of any such selector member to render ineffective all other selector members of higher serial number which are operated simultaneously therewith.

In other words, such interlocking means are provided in association with the normally ineffective selector members so that, after such selector members have been rendered effective by the deposit of a proper coin or coins in the coin-receiving means, selection of only one record will be effected when more than one of the selector members are depressed at the same time. The operator thus is prevented from initiating more playing cycles of the phonograph than the number thereof to which he is entitled by virtue of the prior deposit of a proper coin or coins.

Numerous other objects and advantages of the invention will be apparent as it is better understood from the following description, which, when taken in connection with the accompanying drawings, discloses a preferred embodiment thereof.

Figure 1 is a vertical sectional view of an automatic phonograph embodying the features of the instant invention;

GENERAL

(Reference characters A to V and numerals 77, 85, 181-196, 237 and 246)

Referring more particularly to the drawings, the operating mechanism of the phonograph illustrated as embodying the features of the instant invention is generally of the type disclosed in United States Letters Patent No. 2,159,834, issued May 23, 1929, to P. H. Smyth, Jr., and the alphabetical reference characters used herein are the same as those employed in said patent and designate either identical or similar mechanism. Since this mechanism is described in detail in said patent, a brief and general explanation thereof will be sufficient herein for a complete understanding of the present invention.

The automatic phonograph comprises an outer casing or cabinet A (Figs. 1 and 4) for accommodating a chassis or a frame B for supporting the operating mechanism, amplifier means C, and speaker means D. The chassis B serves as a mounting means for record carrying and reproducing devices which, generally considered, cooperate to translate the irregularities or impulses in the sound track of a record into mechanical vibrations and to convert such mechanical vibrations into electrical impulses. These electrical impulses are then supplied to the amplifier means C and, after amplification, they are converted into sound by the speaker means D. As shown in Figs. 1 and 4, the chassis B includes a horizontally disposed panel E, commonly referred to as a motor board, having an aperture F therein, and carries a turntable G, record reproducer means or tone arm H, a record carrier supporting or mounting assembly I, and a plurality of pivoted, ring-shaped record carriers or trays J arranged one above the other in column or stacked relationship and selectively swingable to and from cooperative relationship with the turntable G. Members K and L provide individual supports for each record carrier J at the end thereof opposite the mounting assembly I, when the record carrier is in its position of cooperation with the turntable G, and when it is in stack, respectively. Supported from and disposed below the motor board E, are a master cam M, a main motor N for driving the same, and a second motor O (Fig. 3) for rotating the turntable G.

Operation of the phonograph is controlled jointly by coin operated means (to be described hereinafter) and record selector control means or predetermining means V, the latter determining the particular position in which a selector finger 77 (Fig. 4) will be stopped in its vertical movement by the master cam M in each cycle of operation of the machine, which will cause a record carrier swinging yoke 85 to move that record carrier J disposed in stack in a position corresponding to the one at which the selector finger 77 has been stopped to swing the same and the record carried thereby into vertical alignment with the turntable G.

The predetermining or selector control means V herein employed is similar to those disclosed in United States Letters Patent No. 2,347,995, issued May 2, 1944, to L. E. Dettle, and the pending applications of D. C. Rockola, Serial No. 553,161, filed September 8, 1944, now Patent No. 2,569,115, issued September 25, 1951 and Serial No. 713,045, filed November 29, 1946, and, as best illustrated in the latter application, includes a plurality of electro-magnetic selector coils 237 (Fig. 10) corresponding respectively to the sev-

eral records in the trays J, and a switch actuating lever 246 (Fig. 3), which are designated in said application Serial No. 713,045 by these same reference numerals.

In the present machine, each of these selector coils 237 is adapted to be energized, respectively, by actuation of one of a plurality of manually operable selector members or push buttons 181 (Figs. 1, 4 and 10) in a manner to be described in detail hereinafter. Upon energization of any selector coil 237, the switch actuating lever 246 is swung counterclockwise from its normally inoperative position of Fig. 3 to close a master switch 182 and to retain said switch in closed position. Such actuating lever 246 is operated in response to energization of any one of the selector coils 237 in the same manner as the corresponding switch actuating member 99 is operated in response to energization of any one of the corresponding selector coils 85 in said Dettle Patent No. 2,347,995. As shown in Fig. 3, a positive lead 183 comprising one side of any suitable source of electrical energy is connected by a lead 184 to one side of the main driving motor N, the other side of which is connected by a lead 185 to one side of a single pole, double throw holding switch 186. The arm of the switch 186 is connected by a line 187 to the arm of the master switch 182, and the other side of the switch 182 is connected to the return or negative lead 188. Consequently, it will be seen that closing of the master switch 182 by the lever 246, resulting from the energization of one of the selector coils 237, will close a circuit through the main driving motor N which will initiate operation of the master cam M. The shaft of the master cam M has a notched disc 189 rigidly secured thereto within the notch of which one end of this actuating lever 246 normally rests, as shown in Fig. 3. As operation of the master cam M is thus initiated, the notched disc 189 is rotated in a clockwise direction (viewing Fig. 3) so that the periphery thereof maintains the switch actuating lever 246 in active position to retain the master switch 182 closed for the remainder of the playing cycle thus initiated, regardless of the return to normal position, during such playing cycle, of the predetermining or selector means V in the manner described in said patent and applications hereinbefore referred to.

Such rotation of the master cam M by the motor N causes lowering of the selector finger 77 to a position opposite the record tray J containing the record corresponding to the selector member or push button 181 which was depressed to initiate the playing cycle, as determined by the corresponding electro-magnetic selector coil 237, thereby energized. Continued rotation of master cam M causes counterclockwise horizontal swinging of selector finger 77 from its position of Fig. 4 to release the selected record tray J, and also swings the yoke 85 in a clockwise direction (as seen in Fig. 4) to carry such record tray J from normal stack position into vertical alignment with turntable G. Continued rotation of master cam M raises turntable G from its normally lowermost position through the displaced record tray J to carry the record into playing position, i. e., to present such record for engagement by the tone arm H.

At this point of operation of the master cam M, the notched disc 189 (Fig. 3) carried thereby has been rotated to present the notch therein to the inner end of the arm of the holding switch 186, and the latter is spring moved from its posi-

tion of Fig. 3 to open the circuit previously described through the main driving motor N to stop the latter and the master cam, and at the same time to close a circuit through the turntable motor O. This latter circuit includes a lead 191 connecting one side of turntable motor O to the positive lead 183 and a lead 192 connecting the other side of the motor to the lower side of the holding switch 186, the circuit being completed through the lead 187 and the master switch 182 to the negative lead 188.

A second notched disc 193 (corresponding to the notched disc 49 in Patent No. 2,159,834) is secured to the vertical shaft of the tone arm H, and as the latter reaches the end of the record groove to complete playing of the selected record, the notch in this disc 193 permits spring closing of a switch 194 (Fig. 3) to reenergize the main driving motor N by completing a circuit therethrough including the leads 184 and 185, a lead 195 connected between the latter and one side of switch 194, a lead 196 connected from the other side of switch 194 to lead 187, and the master switch 182 and negative lead 188. The resulting rotation of master cam M removes the notch in the disc 189 from engagement with the arm of holding switch 186 to return the latter to its position of Fig. 3, thus de-energizing turntable motor O and completing the previously described circuit through main motor N, and the master cam M causes lowering of the turntable G to return the played record to its tray J. As the turntable is lowered from playing position, the master cam functions to return the tone arm H to normal or starting position, which returns the notched disc 193 to its position of Fig. 3 to open the switch 194, and after the played record is deposited on its carrier J, the master cam also functions to swing this record carrier back to its normal stack position.

If only one record has been selected for playing, the completion of the playing cycle, in returning the notched disc 189 to its normal position of Fig. 3, permits spring return of the switch actuating lever 246 to its normal position therein illustrated to open the master switch 182, since the selector slide caused to be moved to active position by energization of the associated selector coil 237 has in the meantime been returned to its normally inactive position in the manner described in the aforementioned patent and applications. However, if more than one record has been selected for playing, the switch actuating lever 246 is maintained in its active position to retain the master switch 182 closed, so that another playing cycle is initiated immediately.

ACCUMULATOR MECHANISM

(Reference numerals 20-179)

The novel operation control means herein disclosed and to be described includes accumulator mechanism substantially identical to that illustrated and described in detail in the co-pending application of J. J. Toolan, Serial No. 431,623, filed February 20, 1942, and issued February 10, 1948, as Patent No. 2,435,933. Consequently, a brief résumé of the operation of this accumulator mechanism herein will be sufficient for a complete understanding of its relationship and co-operation with the novel operation control mechanism hereinafter described, and of which it forms a part, and the same reference numerals as employed in said Toolan application will be used herein with reference to this accumulator mechanism.

Referring more particularly to Figs. 2 and 5, reference numeral 21 indicates in general a coin-receiving and credit register mechanism which is mounted on the casing A at the right side of the phonograph below the motor board E and adjacent the forward end of the casing by means of a suitable backing or supporting plate member 22, and includes coin handling mechanism 23 for receiving coins of different denominations, such as nickels, dimes and quarters, deposited in a coin-receiving chute 20 (Figs. 1 and 4) located at the front of the machine with its upper end adjacent the row of selector members 181. This coin-receiving and credit register mechanism 21 also includes an auxiliary coin-receiving or guiding mechanism 24 (Fig. 5) disposed below the coin handling mechanism 23 and into which the latter guides genuine coins of the denominations above listed to different points of delivery, spurious or counterfeit coins, slugs and the like, being rejected by the coin handling mechanism 23. The coin-receiving and credit register mechanism 21 also includes a control and credit register or accumulator indicated generally by reference numeral 25, and a supporting structure or frame 26 secured to or formed as an integral part of the supporting plate 22.

As shown in Fig. 5, the coin guiding mechanism 24 comprises a vertically disposed quarter coin slot 73, a nickel coin slot 75 disposed laterally of the latter (to the rear of slot 73 viewing Fig. 5), and a dime coin slot 76, into the upper ends of which genuine coins of these different denominations which are deposited in coin chute 20 will be delivered by the coin handling mechanism 23. As any coin falls by gravity through the guiding mechanism 24, it depresses the free, inwardly turned end of an associated accumulator control lever, the quarter lever being designated by reference numeral 79, the dime lever by 82 and the nickel lever by 84. Each of these three accumulator control levers is pivotally mounted on a horizontal shaft 86 supported adjacent its ends by side plates or frame members 95 and 96 of the accumulator 25.

Also supported by these frame plates 95 and 96 is a horizontal shaft 99 (Figs. 2 and 5) upon which are rotatably mounted three laterally spaced register elements or toothed wheels 101, 102 and 103 comprising the main portion of the accumulator 25. An accumulator actuating spring 106 is coiled around the outer end of the shaft 99 and secured at its opposite ends, respectively, to the frame plate 96 and the units order register wheel 101. A horizontal rod or pin 107 is secured at its outer end to the register wheel 101 and extends laterally through apertures 108 and 109 (Fig. 5) provided, respectively, in the register wheels 102 and 103. Springs 112 interconnect the rod 107 with each of the register wheels 102 and 103.

Means are provided for normally restraining the units register wheel 101 against positive actuation, or counter-clockwise rotation as viewed in Fig. 5, by the spring 106, which comprises a latch pawl lever 114 rotatably mounted on a horizontal shaft 116. A substantially U-shaped latch releasing lever 119 is rotatably mounted at its upper ends on shaft 116, and a coil spring 124 interconnects this lever 119 and the rear end of latch pawl lever 114 to normally maintain the forward end of the latter in engagement with the toothed periphery of the units register wheel 101. A coil spring 128 also connected to the latch releasing lever 119 functions to assist

spring 124 in yieldingly maintaining latch pawl lever 114 in active engagement with the units register wheel 101, thus preventing positive rotation of the latter by spring 106.

Also rotatably mounted upon the horizontal shaft 116 are three stop pawl levers 131, having shelf portions 133 formed at their upper ends for cooperation, respectively, with the three register wheels 101, 102 and 103. A coil spring 134 is connected to each of the stop pawl levers 131 to urge the latter in a clockwise direction, as seen in Fig. 5. Each coin actuated accumulator control lever 79, 82 and 84 is provided at its forward end with an upwardly inclined shelf portion 139 cooperating with the lower ends of the stop pawl levers 131 and the lower transverse portion of the latch releasing lever 119. A coil spring 141 is attached to each of the accumulator control levers 79, 82 and 84 to maintain the latter in the normal position of Fig. 5 and to retain the associated stop pawl levers 131 in such position against actuation by their springs 134.

Whenever a nickel is deposited in the coin-receiving chute 20, passes successfully through the coin handling mechanism 23 and into the nickel coin slot 75, it will rotate the accumulator control lever 84 in a counterclockwise direction as viewed in Fig. 5. The shelf 139 on the forward end of lever 84 will thus swing the latch releasing lever 119 clockwise about shaft 116 to remove latch pawl lever 114 from engagement with the units register wheel 101 to permit counterclockwise rotation of the latter by the spring 106. At the same time, as the register wheel 101 starts to rotate, the spring 134 of the associated stop pawl lever 131 will swing the latter clockwise about shaft 116 to present its shelf 133 to the toothed periphery of the units wheel 101. As soon as the coin falling through the guiding mechanism 24 releases the control lever 84, the latter is returned to its normal position of Fig. 5 by its spring 141. During such return movement of the lever 84, springs 124 and 128 return latch pawl lever 114 into engagement with register wheel 101, and the associated stop pawl lever 131 is swung against the action of its spring 134 to remove its shelf 133 from engagement with the register wheel. The paws 114 and 131 thus function as an escapement mechanism to permit positive actuation of the accumulator, comprising a single step or increment of rotation in a counterclockwise direction of the units wheel 101, representing one unit of value. Since the register wheels 102 and 103 are free to rotate at this time, the springs 112 will cause them to accompany the units register wheel 101, the rod 107 and apertures 108 and 109 limiting such movement of wheels 102 and 103 by springs 112.

Deposits of a dime or quarter will similarly actuate the accumulator control levers 82 or 79 which, respectively, will similarly swing latch releasing lever 119 to release latch pawl lever 114 from engagement with the units wheel 101, and permit the associated stop pawl lever 131 to be engaged with either register wheel 102 or 103. If a dime has been deposited, the wheel 102 is thus engaged by its stop pawl lever 131 to limit the resulting rotation of units wheel 101 by spring 106 to two steps or increments of rotation by virtue of aperture 108 restraining further movement of rod 107. Following release of lever 82 by the passage of the dime through the guiding mechanism 24, the resulting re-engagement of latch pawl lever 114 with the units wheel 101

and disengagement of the associated stop pawl lever 131 from register wheel 102 will permit the spring 112 connected to register wheel 102 to move the latter positively a comparable distance. Actuation of accumulator control lever 79 by the deposit of a quarter similarly will permit rotation of the units register wheel 101 through five increments or steps of movement, and follow up movement of register wheel 103 by its spring 112 upon release and return of lever 79, in similar manner. It thus will be seen that the deposit of proper coins of different denominational values in coin chute 20 will result automatically in the positive accumulation of a total in the accumulator 25 equal to the total number of units of value of the coins deposited.

In order to translate such positive actuation of the accumulator 25 into a factor for controlling the phonograph actuating mechanism previously described, the units register wheel 101 is provided with a horizontally disposed insulated pin 148 which normally maintains a spring contact 149 out of engagement with a stationary contact 151 of a master coin switch 152 which is electrically connected by leads 166 and 168 in the control circuit of the machine in a manner to be described more in detail hereinafter. As seen in Fig. 5, the pin 148 normally maintains master coin switch 152 open, and immediately upon the positive accumulation of any total in the accumulator 25, which comprises a counterclockwise rotation of the units register wheel 101, the pin 148 is moved out of engagement with spring contact 149 to permit closing of the master coin switch 152.

Means are also provided for actuating the accumulator 25 negatively, which comprises a debiting solenoid 153 having leads 178 and 179 electrically connected in the control circuit of the machine in a manner to be described in detail hereinafter. A lever 155 comprising the armature of solenoid 153 is normally held in inactive position away from the latter by a spring 156, as shown in Fig. 5, and is provided at its lower end with a pawl 159 in lateral alignment with the units register wheel 101. Energization of solenoid 153 will swing the lever 155 against the action of its spring 156 in a counterclockwise direction (viewing Fig. 5) to cause the pawl 159 to move the units register wheel 101 one step in a clockwise direction. The rod 107 will similarly move the register wheels 102 and 103, so that for each actuation or energization of the debiting solenoid 153 the accumulator 25 will have one unit of value subtracted from the total therein accumulated. As soon as the accumulator has thus been returned step by step to its normal position of Fig. 5, the pin 148 will open the master coin switch 152.

OPERATION CONTROL MECHANISM

(Reference numerals 197-236 and reference characters a-j)

The operation control mechanism herein illustrated, and now to be described, automatically controls the previously described operating mechanism in such manner as to accomplish the hereinbefore enumerated objects of the instant invention, and it includes the coin-receiving and credit register mechanism 21, and specifically the accumulator 25, the master coin switch 152 and the accumulator debiting coil 153, but these are combined and function in an entirely different manner than that disclosed in the Toolan application referred to, in order to obtain the desired

results. In the present invention the manually operable selector members or push buttons 181 normally are ineffective, and the operation control mechanism renders them effective to initiate only a number of playing cycles equivalent to the total value of coins first deposited in the receiving chute 20, and prevents stealing of the selections thus made by subsequent actuation of the selector members 181.

In addition to the members so far described, the operation control mechanism includes an interlocking switch arrangement or assembly 197 (Fig. 9), a make selection switch 198, a lock-out switch 199, selector member or push button interlocking means 201 (Fig. 10), and a credit light 202 (Figs. 4 and 10).

A hot or positive lead 203 and a common or negative lead 204 are shown in Fig. 10 as comprising a suitable source of electrical energy for the operation control mechanism circuit. These leads, together with leads 205 which are individually connected to one side of the selector coils 237 (the other sides of which are illustrated as being grounded, which is the same as being connected to the common lead 204), form a cable indicated diagrammatically at 206. At the other end of the cable 206, the hot lead 203 is connected to contact *a* of an electrical socket 207 adapted to receive a companion plug 208 shown in Fig. 9. The hot lead 203 is also connected in Fig. 10 to the arm of a single pole double throw selector switch 209 operably associated with the number one selector member or push button 181, a similar switch 209 being provided for each selector member. The upper contact of this number one selector switch 209 is connected to the arm of the switch 209 associated with the number two selector member 181, and similar connections are provided for all of the switches 209, so that all of these switches, when in their normal position of Fig. 10, are connected in series and to a lead 211 which is connected to a contact *b* of the socket 207. The lower contacts of each of these selector switches 209 are connected in series by a lead 212 to a contact *c* of socket 207.

A second group of selector switches 213 disposed, respectively, below selector switches 209 and operatively associated with the push buttons 181, have their arms normally connected in series by means of their upper contacts and by a lead 214 to a contact *d* of the socket 207. The other or lower contacts of these lower selector switches 213 are connected, respectively, to the leads 205 extending as part of cable 206 to the associated selector coils 237. Since operation or depression of any selector member or push button 181 will move the arm of the associated lower selector switch 213 out of engagement with its upper contact, the circuit from lead 214 thus will be broken to all selector switches 213 associated with higher serially numbered push buttons 181. Consequently, these lower selector switches 213 comprise the selector member interlocking means 201 previously enumerated. One side of the credit light 202 is connected to lead 211, and the other side is connected by a lead 215 to contact *e* of the socket 207.

Contact *f* of socket 207 is connected to the common or negative lead 204. It will be appreciated that the wiring diagrams shown in Figs. 9 and 10 together comprise a schematic illustration of the operation control mechanism circuit, the plug 208 being engaged with the socket 207 in well known manner, with the correspondingly lettered contacts thereof engaged with each other to in-

70

Contact *f* of socket 207 is connected to the common or negative lead 204. It will be appreciated that the wiring diagrams shown in Figs. 9 and 10 together comprise a schematic illustration of the operation control mechanism circuit, the plug 208 being engaged with the socket 207 in well known manner, with the correspondingly lettered contacts thereof engaged with each other to in-

11

terconnect the instrumentalities included in these two figures, in a manner to be described more in detail hereinafter.

Referring now to Figs. 5 and 9, the interlocking switch arrangement or assembly 197 is shown as comprising a mounting strip 216 connected in any suitable manner to and supported by the frame structure 26 of the coin-receiving and credit register mechanism 21. The means employed for attaching the mounting strip 216 may also be used to secure thereto a pair of coil mounting brackets 217 for supporting, respectively, an electro-magnetic reset coil 218 and a similar starting coil 219. Mounted upon the central portion of the strip 216 in any suitable manner is a snap or pin type switch 221 of well known construction having four contacts *g*, *h*, *i* and *j* (Fig. 9). The contact bridging element of this switch 221 normally interconnects its contacts *g* and *h*, and upon movement of its pin to the left (viewing Fig. 9), it is snapped over to interconnect the contacts *i* and *j*. Such movement from the normal position of the parts illustrated in Fig. 9 is accomplished by the plunger of the starting coil 219 upon energization of this coil. Conversely, subsequent energization of resetting coil 218 will return its plunger to the position illustrated in Fig. 9 to reset switch 221 to its normal position therein shown.

As illustrated in Fig. 9, contact *g* of interlocking switch 221 is connected by a lead 222 to contact *b* of plug 208. Contact *h* of switch 221 is connected by a lead 223 to one side of the starting coil 219, the other side of the latter in turn being connected to lead 168. Contact *i* of switch 221 is connected by a lead 224 to the movable contact of lock-out switch 199, the stationary contact of the latter being connected by lead 179 to one side of the debiting coil 153, and the other side of the latter being connected by lead 178 to contact *c* of plug 208. Contact *j* of switch 221 is connected by a lead 225 to contact *f* of plug 208. The stationary contact of make selection switch 198 is connected by a lead 226 to contact *d* of plug 208, and the movable contact of switch 198 is connected by a lead 227 to one side of the reset coil 218, the other side of the latter being connected by a lead 228 to contact *a* of the plug 208.

Referring now to Figs. 6, 7 and 8, a modified form of interlocking arrangement or assembly 197' is therein illustrated which is similar in function to the interlocking assembly 197 and comprises a mounting strip 216', and the same coil mounting brackets 217, reset coil 218 and starting coil 219 as are used in interlocking assembly 197. This interlocking arrangement 197', however, employs a snap or pin-type switch 229 (mounted on the strip 216'), which has three contacts 231, 232 and 233 instead of the four contacts of switch 221. The bridging element of the switch 229 normally interconnects contacts 231 and 232, and is adapted to be thrown from this normal position by the plunger of starting coil 219, upon energization of the latter, to interconnect contact 233 with contact 232. When this modified interlocking arrangement 197' is substituted in the operation control mechanism circuit of Fig. 9 for the interlocking assembly 197, its contacts 231 and 233 are connected, respectively, to the leads 222 and 225, similarly to the contacts *g* and *j* of switch 221. The contact 232, however, is connected both to the lead 223 and the lead 224.

As is best illustrated in Figs. 2 and 5, the lock-out switch 199 is secured in any suitable manner

to a mounting bracket 234 which in turn is secured to the inner side plate 95 of the accumulator 25. This lock-out switch 199 comprises a single pole single throw microtype switch of well known construction, the rotatable pin actuating element 235 of which is spring urged to maintain the switch in open condition. A restraining lever 236 has the upper end thereof extending through a suitable aperture in the pin 235 and, with the switch 199 mounted in the manner illustrated in Figs. 2 and 5, the lower end of the lever 236 is disposed in engagement with the forward edge of the lower transverse portion of the latch releasing lever 119 of accumulator 25. In this normal position, lever 119 maintains restraining lever 236 and the pin actuating element 235 against actuation of the spring of the latter to retain lock-out switch 199 in closed condition. Whenever a suitable coin is delivered by the coin handling mechanism 23 to the auxiliary coin receiving mechanism 24 to actuate any one of the accumulator control levers 79, 82 or 84 to cause positive actuation of accumulator 25, the resulting clockwise swinging of latch releasing lever 119 (as viewed in Fig. 5) results in automatic opening of lock-out switch 199, and the latter is closed only after completion of such positive actuation of the accumulator, which includes return clockwise swinging of latch releasing lever 119 to its position of Fig. 5. This normal position of restraining lever 236 and the normally closed condition of lock-out switch 199 are illustrated in the wiring diagram of Fig. 9, and so long as the accumulator 25 is not in the process of being actuated in a positive direction, the switch 199 will remain closed, but it will be opened automatically during any positive actuation of the accumulator.

OPERATION

Normally the operation control mechanism circuit from the hot or positive lead 203 and contact *a* of socket 207 in Fig. 10 is completed through the upper bank of selector switches 209 to contact *b* of socket 207, and also through the upper bank of selector switches 209 and credit light 202 to contact *e* of socket 207. As will be seen from Fig. 9, however, the circuits from contacts *b* and *e* of plug 208 normally are broken by the master coin switch 152 being open to prevent their completion to contact *f*, which is connected to the return or negative lead 284 (Fig. 10). With the circuits in this normal inoperative condition, depression of any one, or more, of the manually operable selector buttons 181 will have no effect for the following reasons. Such operation of a selector button, as seen in Fig. 10, will complete a circuit therein from the hot lead 203 and contact *a* to contact *c* through the upper selector switch 209 thus closed and lead 212. But from *c* the circuit cannot be completed to *f* in Fig. 9, because the interlocking switch 221 is open between its contacts *i* and *j*. Such operation of any selector button 181 also will complete a return circuit in Fig. 10 from *d* through lead 214 and the lower selector switch 213 to the corresponding selector coil 237 in the coil bank assembly of the predetermining means V, but the circuit in Fig. 9 from *a* to *d* is not complete because the make selection switch 198 normally is open. Consequently, all of the selector members or push buttons 181 normally are completely ineffective to select a record for playing by energizing their associated selector coils 237.

Deposit of any proper coin to actuate the accumulator mechanism 25 in the manner previ-

ously described, however, will close the master coin switch 152 to render effective the normally ineffective selector buttons 181. Such coin deposit automatically causes a circuit to be completed from the hot lead 203 and contact *a* of Fig. 10 through the upper bank of selector switches 209 and lead 211 to *b*, and from *b* in Fig. 9 through contacts *g* and *h* of the interlocking switch 221, starting coil 219, and master coin switch 152 to *f*, and from *f* in Fig. 10 to the return or common lead 204, thereby to energize starting coil 219 to break the connection between contacts *g* and *h* and interconnect contacts *i* and *j* of interlocking switch 221. At the same time, credit light 202 of Fig. 10 will be energized or lighted automatically by a circuit from hot lead 203 and contact *a* being completed through the upper bank of selector switches 209, the light 202 and lead 215 to *e*, and from *e* in Fig. 9 through master coin switch 152 to *f*, and from *f* in Fig. 10 to the return or common lead 204, thereby to indicate to the operator that he has a credit in the machine and should make a selection by depressing one of the selector buttons 181.

Subsequent depression of any one of the selector buttons 181 will debit one unit of value from the accumulator mechanism 25, reset the interlocking switch assembly 197 to normal condition, and energize the associated selector coil 237 to select the corresponding record for playing and to initiate a playing cycle by closing the master switch 182 (Fig. 3), as previously described. The depression of a selector button 181 will complete the circuit rendered effective by closing of master coin switch 152 from hot lead 203 and contact *a* of Fig. 10 through the operated upper selector switch 209 and lead 212 to *c*, and from *c* in Fig. 9 through debit coil 153, lock-out switch 199 and contacts *i* and *j* of interlocking switch 221 to *f*, and from *f* in Fig. 10 to the return or common lead 204, thus energizing debit coil 153 to return accumulator wheel 101 one step backwardly (clockwise in Fig. 9). As this one step debiting actuation of accumulator wheel 101 is being completed (i. e., during the final portion of the operating stroke of pawl 159), the make selection switch 198 will be permitted to close by spring action to complete a circuit for simultaneously energizing the reset coil 218 and the selector coil 237 corresponding to the actuated selector member 181. This circuit runs from *a* in Fig. 9 through reset coil 218 and make selection switch 198 to *d*, and from *d* of Fig. 10 through lead 214 and the lower operated selector switch 213 to the associated grounded selector coil 237. This energization of reset coil 218 must thus be delayed until the end of the operative stroke of pawl 159 by debit coil 153, because the latter is in the circuit including contacts *i* and *j* of the interlocking switch 221, and the reset coil opens these contacts *i* and *j* and closes contacts *g* and *h* of interlocking switch 221 to recondition the control circuits as above described to their normal inoperative condition, if the one step backward or debiting actuation of accumulator wheel 101 by the debit coil 153 has opened the master coin switch 152. On the other hand, if more than one positive unit of value has been introduced into the accumulator mechanism by previous deposit of proper coins, so that the one step debiting actuation of accumulator wheel 101 has not opened master coin switch 152, then starting coil 219 immediately and automatically will be re-energized, as above described, to again

break the connection between contacts *g* and *h* and interconnect contacts *i* and *j* of interlocking switch 221 to re-energize credit light 202 and render selector buttons 181 effective to accomplish the selection of another record for playing following playing of that previously selected. Thus selector buttons 181 are rendered effective automatically following each successive operation thereof so long as any positive value remains in the accumulator 25, and as soon as a selection (operation of a selector button 181) removes the last unit of value remaining in the accumulator to open master coin switch 152, the selector buttons all are immediately rendered ineffective. The number of playing cycles or selections available are determined by the accumulator 25, as operated positively by the deposit of proper coins and negatively by the making of successive selections, and so long as any positive value remains in the accumulator, the credit light 202 will be energized to apprise the operator of that fact. Once a successive number of selections have been made equal to the total units of value entered in the accumulator by the deposit of proper coins, further operation of any of the selector buttons 181 is ineffective, and there is no possible way for anyone to steal such selections or to prevent the playing thereof or the substitution therefor of other selections.

In addition to the proper timing of the sequential operations in depositing a coin or coins and making selection by manually depressing one or more selector buttons 181, the interlocking switch assembly 197, including the switch 221, serves to condition the selector circuit for completion by closing of the make selection switch 198 independently of the master coin switch 152 to insure energization of a selector coil 237 when the last selection is made to which an operator rightfully is entitled. But for this interlocking switch mechanism being included in the circuit, energization of a selector coil 237 would not be effected upon depression of its associated selector button 181 after deposit of a single nickel to positively actuate the accumulator and close the switch 152. In other words, it is necessary for fool-proof operation that the accumulator first be returned to normal position after the positive coin actuation thereof and upon depression of a selector button 181, before a corresponding selector coil 237 is energized. In order to insure such timed operation, energization of any selector coil 237 is made to depend upon the closing of the make selection switch 198 and this switch 198 is closed only in the final increment of movement of the armature lever 155 of the debit coil 153. However, actuation of this armature 155 effects negative actuation of the accumulator, which will open the master coin switch 152 if only one increment of value remains in the accumulator at this time, before the make selection switch 198 is closed. The circuit to the selector coils 237 therefore cannot include the master coin switch 152. Otherwise, deposit of a nickel and subsequent depression of a selector button 181 would not energize the associated selector coil 237, and the last selection made after positive actuation of the accumulator for any plurality of increments of value likewise would be lost. Rather, master coin switch 152 is opened when credit is exhausted in response to the energization of the debit coil 153, and immediately as this is accomplished, switch 198 is closed to instantaneously complete the selector circuit from contact *a* of plug 208 in Fig. 9 through lead

15

228, reset coil 218, and leads 221 and 226 to contact *d*. Referring to Fig. 10, the completion of this circuit also results in instantaneous energization of the associated selector coil 237, since the switch 213 of the selector button 181 depressed is closed to complete the circuit from contact *d* of socket 207 through lead 214 and switch 213 to the appropriate lead 205. This energization of the selected coil 237 is accomplished despite the previous opening of the master coin switch 152. Of course, continued holding of this depressed selector button 181 accomplishes nothing, nor will immediate depression of lower numbered buttons 181 result in energization of their associated selector coils 237, since such instantaneous closing of make selection switch 198 also results in immediate energization of the reset coil 218 to break the circuit through debit coil 153, so that spring 156 immediately opens the make selection switch 198.

It will be understood from Fig. 10 that only that number of selections to which an operator is entitled by virtue of the deposit of proper coins may be effected, since simultaneous operation of more than one selector button 181 can result only in effecting one selection, which will be that corresponding to the lowest numbered selector button, or that farthest to the right in Fig. 10, which is depressed. Such result obtains because the lower selector switch 213 operated by depression of such lowest numbered selector button will break the previously described circuit from contact *d* of socket 207 and lead 214 to all such lower selector switches 213 to the left thereof at the same time that it completes the above-noted circuit to its associated selector coil 237.

It has been found that a dishonest operator, if sufficiently skillful, may effect selections in greater number than the total units of value of coins deposited, to which he is not entitled, if after depositing one coin, such as a nickel, he deposits another similar coin and, with the proper timing, successively depresses a plurality of selector buttons during the short time interval in which the coin operated latch releasing lever 119 of the accumulator is completing its full reciprocal movement resulting from the deposit of such second coin. Means are provided, however, for preventing such erroneous operation of the instant mechanism. This means comprises the lock-out switch 199 which is normally closed as shown in Fig. 9, being held closed by the latch releasing lever 119 of the accumulator, but which is automatically sprung opened during any positive actuation of the accumulator, by virtue of the latch releasing lever 119 being swung away from the restraining lever 236. Thus, during any positive actuation of the accumulator, the selection effecting circuit which includes this lock-out switch 199 is broken, so that all of the selector buttons 181 are temporarily rendered ineffective during positive actuation of the accumulator. Also, since such opening of lock-out switch 199 during positive actuation of the accumulator 25 prevents energization of debit coil 153, it effectively forestalls any jamming or breakage of parts that might otherwise occur from attempted simultaneous positive and negative actuation of the accumulator.

It is thought that the invention and many of its attendant advantages will be understood from the foregoing description, and it will be apparent that various changes may be made in the form, construction and arrangement of the parts without departing from the spirit and scope of the

16

invention or sacrificing all of its material advantages, the form hereinbefore described being merely a preferred embodiment thereof.

I claim:

1. In a machine having a plurality of selector members selectively operable to control successive cycles of operation thereof, and mechanism for receiving coins of predetermined value; operation control mechanism, comprising an accumulator operable in response to the deposit of coins in said receiving mechanism to accumulate positively a total of predetermined incremental values corresponding to the total values of the coins deposited, a master switch normally maintained open by said accumulator and automatically closed in response to positive actuation of said accumulator, debiting mechanism operable in response to operation of any said selector member to actuate said accumulator negatively to subtract a said predetermined incremental value from the total accumulated therein in response to deposited coins, an electrical circuit including said selector members, said master switch and said debiting mechanism, and an interlocking switch arrangement interposed in said circuit and comprising normally open contacts operable to maintain a portion of said circuit open to prevent actuation of said debiting mechanism in response to operation of any said selector member, and a starting coil automatically operable, upon closing of said master switch in response to the deposit of any proper coin in said receiving mechanism, to close said normally open contacts to condition such circuit for closing by subsequent operation of any said selector member.
2. In a machine having a plurality of selector members selectively operable to control successive cycles of operation thereof, and mechanism for receiving coins of predetermined value; operation control mechanism, comprising an accumulator operable in response to the deposit of coins in said receiving mechanism to accumulate positively a total of predetermined incremental values corresponding to the total values of the coins deposited, a master switch normally maintained open by said accumulator and automatically closed in response to positive actuation of said accumulator, debiting mechanism operable in response to operation of any said selector member to actuate said accumulator negatively to subtract a said predetermined incremental value from the total accumulated therein in response to deposited coins, an electrical circuit including said selector members, said master switch and said debiting mechanism, and an interlocking switch arrangement interposed in said circuit and comprising normally open contacts operable to maintain a portion of said circuit open to prevent actuation of said debiting mechanism in response to operation of any said selector member, said master switch and said debiting mechanism, and an interlocking switch arrangement interposed in said circuit and comprising normally open contacts operable to maintain a portion of said circuit open to prevent actuation of said debiting mechanism in response to operation of any said selector member, and a starting coil automatically operable, upon closing of said master switch in response to the deposit of any proper coin in said receiving mechanism, to close said normally open contacts to condition such circuit for closing by subsequent operation of any said selector member.
3. In a machine having a plurality of selector members selectively operable to control successive cycles of operation thereof, and mechanism

for receiving coins of predetermined value; operation control mechanism, comprising an accumulator operable in response to the deposit of coins in said receiving mechanism to accumulate positively a total of predetermined incremental values corresponding to the total values of the coins deposited, a master switch normally maintained open by said accumulator and automatically closed in response to positive actuation of said accumulator, debiting mechanism operable in response to operation of any said selector member to actuate said accumulator negatively to subtract a said predetermined incremental value from the total accumulated therein, an electrical circuit including said selector members, said master switch and said debiting mechanism, and an interlocking switch arrangement interposed in said circuit and comprising normally open contacts operable to maintain a portion of said circuit open to prevent actuation of said debiting mechanism in response to operation of any said selector member, normally closed contacts, and a starting coil in series with said normally closed contacts so as to be automatically operable, upon closing of said master switch in response to the deposit of any proper coin in said receiving mechanism, to close said normally open contacts and open said normally closed contacts to condition such circuit for closing by subsequent operation of any said selector member, and said interlocking switch arrangement including a reset coil operable automatically, in response to each such actuation of a said selector member, to re-open said normally open contacts and re-close said normally closed contacts to cause another automatic operation of said starting coil if said master switch is closed, whereby said circuit is again conditioned for closing by subsequent actuation of any said selector member, until the resulting successive actuations of said debiting mechanism are equal in number to the total of the predetermined incremental values positively accumulated in said accumulator responsive to coin deposits, said master switch then being returned to normal open condition by said accumulator, and said interlocking switch arrangement thereupon being maintained in normal condition to render ineffective all of said selector members.

4. In an automatic phonograph having a source of electrical energy including a hot lead and a return lead, a selector, including a plurality of serially numbered and manually operable control members, an upper selector switch and a lower selector switch operatively associated with each of said control members and normally disposed in the upper of two possible positions, said upper selector switches each having an upper and a lower pole with the upper poles normally connected in series with each other and said hot lead by said upper switches when in said upper positions, said lower selector switches each having an upper and a lower pole with the upper poles normally interconnected in series by said lower switches when in said upper positions, and a selector coil electrically connected between each of the lower poles of said lower selector switches and said return lead and adapted, when energized, to initiate and control a playing cycle of the phonograph; a credit light connected at one

side to the upper pole of the upper selector switch associated with the highest serially numbered control member, coin-receiving mechanism, an accumulator automatically operable positively in response to the deposit of a genuine coin or coins in said coin-receiving mechanism to accumulate a total therein equal to the total units of value of said coins, debiting mechanism including a debit coil operable, when energized, to actuate said accumulator negatively to subtract a unit of value from the total therein accumulated, a normally open master coin switch automatically closed in response to positive actuation of said accumulator and opened by said accumulator when the latter is returned to zero by said debiting mechanism, a normally closed lock-out switch connected at one side to one side of said debiting coil and operatively associated with said accumulator so as to be opened automatically during positive actuation of the accumulator, the other side of said debiting coil being connected to said lower poles of said upper selector switches, a normally open make selection switch operatively associated with said debiting mechanism so as to be closed upon operation of the latter and connected at one side to the lower selector switch associated with the lowest serially numbered control member, and an interlocking assembly, including a starting coil, a reset coil and an interlocking switch having normally interconnected contacts and normally disconnected contacts, said starting coil being adapted to disconnect said normally interconnected contacts and to interconnect said normally disconnected contacts when energized, and said reset coil being adapted to return said interlocking switch to normal condition when energized, one of said normally interconnected contacts being connected to one side of said starting coil, the other side of said starting coil being connected to one side of said master coin switch and to the other side of said credit light, another of said normally interconnected contacts being connected to the upper pole of the upper selector switch associated with the highest serially numbered control member, one of said normally disconnected contacts being connected to the other side of said master coin switch and to said return lead and the remaining contact being connected to the other side of said lock-out switch, and said reset coil being connected at one side to said hot lead and at the other side to the other side of said make selection switch.
